INVENTOR:

Matthew C. Day
by Chas. H. Luther

ATTORNEY:

UNITED STATES PATENT OFFICE.

MATHEW C. DAY, OF PROVIDENCE, RHODE ISLAND.

SEPARABLE EMBLEM BUTTON.

Application filed May 24, 1922. Serial No. 563,353.

To all whom it may concern:

Be it known that I, MATHEW C. DAY, a citizen of the United States, residing at Providence, in the county of Providence and State of Rhode Island, have invented a new and useful Improvement in Separable Emblem Buttons, of which the following is a specification.

My invention has reference to an improvement in separable buttons and more particularly to an improvement in separable emblem buttons.

In the usual construction of separable emblem buttons the separable parts screw together and the point for preventing the button from turning in the button hole, is usually soldered on to one of the members.

The object of my invention is to simplify the construction of a separable emblem button, whereby the separable members are easily secured together, are materially harder to separate, thereby avoiding loss of one or both of the button members and the whole button is formed of three parts only.

25 A further object of my invention is to form the point or cloth penetrating member integral with one of the button parts, thereby eliminating the use of solder.

My invention consists in the peculiar and 30 novel construction of a separable emblem button, said separable emblem button having details of construction, as will be more fully set forth hereinafter and claimed.

Figure 1 is a side view of my improved 35 separable emblem button showing the same separated in full lines and closed in broken lines.

Figure 2 is a post end view of the spring 40 post member.

Figure 3 is a central sectional view 45 through the button, in the closed position, and

Figure 4 is a perspective view of the shoe 50 cap.

In the drawing 5 indicates the head member, 6 the shoe member and 7 the shoe cap of my improved separable emblem button.

The head member 5 has a flat head 8, a 55 hollow oval stem 9, an oval continuous slightly rounded external ledge 10 and an oval cone shape end 11, all formed integral from sheet metal.

The shoe member 6 has a round inverted saucer shaped base 12 merging into an oval 55 tubular spring post 13 which is split into a

plurality of spring post members 14, 14 by slits 15, 15 which extend from the base 12 into the post 13, as shown in Figure 2, all formed integral from sheet metal.

The shoe cap 7 has a round flat head 16, 60 narrow lips 17, 17 and oppositely disposed V shaped pointed members 18, 18, all formed integral from sheet metal, as shown in Figure 4. The cap 7 is secured to the shoe member 6 over the base 12 by spinning the 65 lips 17, 17 over the edge of the base 12, as shown in Figure 1 and where the post 13 and the base 12 meet there is formed an internal ledge 19 on each of the spring post members 14, 14, as shown in Figure 3. 70

By this construction there is only three parts to the button. The pointed members 18, 18 stand up parallel with the spring post 13 and penetrate the cloth at each side of the button hole, thereby preventing the shoe 75 from turning. The oval post prevents the button from turning in a button hole. After the spring post 13 is inserted through the button hole the stem 9 is forced into the spring post against the spring tension of 80 the spring post members 14, 14, to its limit. The external ledge 10 on the stem 9 now snaps under the internal ledges 19, 19 on the post 13 thereby firmly securing the parts together under spring tension. By the construction of the cone shaped end 11 and external ledge 10 on the stem 9 and the internal ledges 19, 19 on the spring members 85 14, 14, of the post 13 the button members are easily closed or snapped together but 90 considerable force must be used to separate the button, thereby preventing accidental separation of the button. An emblem may be formed on the cap 7 or the emblem may be secured to the head 8 in any well known 95 way.

Having thus described my invention I claim as new:

1. In a separable emblem button, a head member having a flat head, a hollow oval stem, an external ledge and a cone shaped end, a shoe member having a round saucer shaped base merging into an oval tubular spring post split into a plurality of spring post members each having an internal ledge 100 and a shoe cap having a head, lips on the head over the edge of the base on the shoe member and a pointed member on and formed integral with the cap, for the purpose as described. 105

- 2
2. In a separable emblem button, a shoe cap having a head, lips on the head and oppositely disposed pointed members on the ¹⁰ edge of the head, all formed integral, for the purpose as described.
  5. members each having an internal ledge at the junction of the base and the post, all formed integral, for the purpose as described.
  3. In a separable emblem button, a shoe

In testimony whereof, I have signed my name to this specification.

MATHEW C. DAY.
